UNITED STATES PATENT OFFICE.

FRANCIS D. HAGAN, OF MCKINNEY, TEXAS.

CATTLE-GUARD.

1,076,420.

Specification of Letters Patent. Patented Oct. 21, 1913.

Application filed March 8, 1913. Serial No. 752,815.

To all whom it may concern:

Be it known that I, FRANCIS D. HAGAN, a citizen of the United States, residing at McKinney, in the county of Collin and 5 State of Texas, have invented certain new and useful Improvements in Cattle-Guards, of which the following is a specification.

My invention relates to cattle guards and relates particularly to that class of cattle 10 guards which comprise a plurality of pivoted members each adapted to rock to an inclined position when stepped upon.

The object of the invention is to provide a novel manner of mounting the pivoted 15 members upon the rail ties, and to form the members in such a manner that when the same is subjected to displacement by an animal's foot, a certain portion of the member will come into sudden contact with the 20 foot, frightening the animal and preventing a further attempt to cross the cattle guard.

The object of the invention is finally to provide a device of the character described that will be strong, durable, simple and ef- 25 ficient and comparatively easy to construct.

With these and various other objects in view my invention has relation to certain novel features of construction and operation, an example of which is described in 30 the following specification, and illustrated in the accompanying drawing, wherein:

Figure 1 is a plan view showing several sections of my cattle guard mounted between the rails of a track. Fig. 2 is a sectional view of the same taken upon the line $x-x$ of Fig. 1. Fig. 3 is a detail fragmentary view showing an end portion of one of my cattle guard sections showing also the projecting extremity of the bar which forms 40 a pivotal support for said section. Fig. 4 is a vertical sectional view of two sections of my cattle guard, one of the same being shown in its displaced position, the plane of section being transverse with the ties.

Referring now more particularly to the drawing, wherein like reference characters designate similar parts in all the figures, the numeral 1 denotes the rails of a track and 2 designates the rail ties. Above each 50 tie there is longitudinally mounted a bar 3, having its extremities provided with slots 4, through each of which is passed a spike 4^a, serving the double purpose of securing the correlated bar extremity and the adjacent rail to the tie into which said spike 55 is driven. The extremities of said bars 3

will preferably rest upon the base portions of the rail 1 as is best shown in Fig. 2. Upon each bar 3 there is pivotally mounted a cattle guard section comprising a sheet metal plate bent to form three integral parts respectively numbered 5, 6 and 7. A pair of U-shaped brackets 8 secured to the under side of the portion 5 of each member establish a pivotal relation between said member and one of the bars 3. The portion 6 has the nature of a rib projecting upwardly at a slight inclination toward the portion 5 and formed by producing a fold in the metal plate. The portion 7 comprises a folded portion of each member normally having contact with one edge of the correlated tie as is clearly shown in Fig. 4. The portion 5 of each member projects in a substantially horizontal position some distance 75 beyond the correlated tie under normal conditions. When the parts are in their normal condition, narrow spaces 9 are formed between the adjacent members of the cattle guard as is best seen in Fig. 1.

When an animal attempts to gain a foot-hold between any two of the ribs 6, one of the cattle guard members in which said ribs are embodied will yield under the pressure of the animal's foot and will assume the inclined position shown at the right hand side of Fig. 4. The animal's footing will thus be completely lost, and at the same time the rib 6 will come into sudden contact with the animal's ankle tending to frighten the 90 animal and to further prevent any of the animal's weight from being rested upon the foot inserted between the two cattle guard members. Thus it is apparent that my cattle guard will afford absolutely no foot- 95 ing to cattle and will effectually prevent the cattle from crossing any portion of the track equipped in the manner above described.

The invention is presented as including all such modifications as come within the 100 scope of the following claims.

What I claim is:

1. A cattle guard member, comprising an elongated metal plate, mounted longitudinally upon a track tie, and provided with 105 a pivotal axis parallel with said tie, the member being normally substantially horizontal at one side of the pivotal axis, and having at the other side of said axis an up-standing rib parallel with the tie, a pre- 110 ponderance of weight being disposed at the side of the member provided with said rib,

normally producing contact between the edge of said side and the corresponding edge of the tie, the member being swung to an inclined position when weight is brought upon its horizontal portion.

2. A cattle guard member, comprising a bar spaced above a rail tie and having its extremities respectively mounted upon the base portions of the track rail, and an elongated metal plate pivoted upon said bar, a preponderance of the weight of said member being disposed at one side of the bar, normally producing contact between the edge of said side and the corresponding edge 10 of the tie, the member being swung to an inclined position when weight is brought upon its other side, and an upstanding rib extending longitudinally of the plate.

3. In a cattle guard, a plurality of elongated plates, each having a longitudinal rib and flat portions on each side of the rib, said flat portions of each plate being disposed at an angle to each other, and a plurality of bars, each pivotally supporting 25 one of the plates and having its ends fixed.

4. In a cattle guard, a plurality of elongated plates, each having a longitudinal rib and flat portions on each side of the rib, said flat portions of each plate being disposed at an angle to each other, the rib of each plate being inclined over one of the 30 flat plate portions so as to slightly overhang the same, and a plurality of bars, each piv-

totally supporting one of the plates and having its ends fixed.

5. In a cattle guard, the combination with a tie, of a bar mounted longitudinally over the tie, and an elongated metal plate hinged on said bar and having two flat portions extending from a longitudinal upstanding rib, one of said flat plate portions being inclined downward with relation to the other, the plate being hinged on the bar so that a preponderance of weight is on the side carrying the rib and the inclined portion whereby the inclined portion normally rests against the tie.

6. In a cattle guard, the combination with adjacent ties, of bars, one mounted over each tie, an elongated metal plate hinged on each tie and having an elongated upstanding rib and tread portions on each side of the rib, one of the plate tread portions being inclined and normally resting on the tie, the plates being disposed so that the inclined tread portion of one is presented toward the relatively opposite tread portion of the other plate between the ties.

In testimony whereof I have signed my name to this specification in the presence of 60 two subscribing witnesses.

FRANCIS D. HAGAN.
